ATTORNEY

UNITED STATES PATENT OFFICE.

CHARLES HAMMER, OF HOLLIS COURT BOULEVARD, NEW YORK.

METAL CAP.

Application filed January 17, 1924. Serial No. 686,708.

To all whom it may concern:

Be it known that I, CHARLES HAMMER, a citizen of the United States, residing at Hollis Court Boulevard, in the county of Queens and State of New York, have invented certain new and useful Improvements in Metal Caps, of which the following is a specification.

This invention relates to caps, particularly metal caps for containers, such as glass containers, particularly catchup bottles, the object of the invention being to provide an improved metal cap which can be made of relatively thin sheet metal and readily attached and easily removed by the use of a coin, and which cap is of simple construction, easily manufactured, inexpensively produced and efficient in use, and which can be readily snapped on for reuse.

20 In the drawings accompanying and forming a part of this specification, Fig. 1 illustrates a glass container in the form of a catchup bottle having this improved cap applied thereto, which latter is shown in section; Fig. 2 is a side view of the cap applied to a bottle; and Fig. 3 is an enlarged section of the upper portion of the bottle and of this improved cap.

Similar characters of reference indicate corresponding parts in the several views. Before explaining in detail the present improvement and mode of operation thereof, I desire to have it understood that the invention is not limited to the particular character or size of cap herein shown or to details of construction and arrangement of parts which are illustrated in the accompanying drawings, since the invention is capable of other embodiments and applicable to other kinds of caps, and therefore the phraseology which I employ is for the purpose of description and not of limitation.

The glass container in the present instance is shown as a catchup bottle 2 having spaced shoulders 3 and 4. The mouth of the bottle has a shouldered lip 5 and is adapted to be sealed by a suitable sealing disk or liner 6 which may be in the form of a disk of cork located within the cap. This improved bottle however forms the subject matter of a separate application filed herewith, Serial No. 686,707 filed January 17, 1924.

This improved cap in the present instance is shown as a two-piece cap, although in some forms thereof, particularly when the skirt is of less depth, the cap may be made

in one piece. As shown the top thereof comprises a disk 7 seamed or interlocked with a depending seamed skirt or flange 8 which may have corrugations if desired to assist in the manipulation of the cap as well as to strengthen the skirt of the same. The depending skirt which may be of any suitable depth, is in the present instance shown of that depth which particularly adapts it for use as a catchup cap and therefore the flange is shown as having a depth usually as great as the diameter of the cap. The lower edge of the flange is bent upon itself to form a curled, rolled, beaded or stiffened lower edge 10 frequently called in this art a wire edge, although no wire is therein.

Above this rolled or beaded edge the unstiffened metal of the skirt is inset or impressed as at 11 around the cap to form an annular holding bead underlapping the shoulder 3 of the container. This insetting is done in the first instance when the bottle is sealed by a suitable machine, whereupon the container is efficiently sealed. In the hands of the user however, the cap can be readily removed or pried off by the insertion of a coin as 12 under the rolled edge and between it and the shoulder 4 of the container, whereupon the cap can be easily pried off. When it is desired to reseal the bottle the cap can be readily snapped on and subsequently removed in the same manner.

Thus the cap has a comparatively smooth interior free from any threads or holding lugs or other means to become messed up and clogged by the contents of the container, thus providing a highly sanitary and practical cap in which the holding means is located above the lower strengthened or rolled edge of the cap but adjacent thereto, this holding means being in the form of an annular impressed bead entirely independent of the rolled edge of the cap and formed from the unstiffened metal of the skirt itself above and free of the stiffened or rolled edge so that the bending inward of the skirt will not disturb or affect such rolled edge. Thus the cap comprises in the present instance an annular holding bead located above an annular outturned rolled edge, the skirt metal between the two beads flaring outward as at 13, whereby a coin may be readily inserted and leverage used against the curled edge and lower shoulder 4, the shoulder forming the fulcrum for the coin, to pry off the cap. Thus while the annular bead and the out-

turned curled edge are located in close proximity to each other, whereby one strengthens and reinforces the other, they are nevertheless so spaced from each other by the flaring part 13 that the action of one is not interfered with by the other and yet both are located at the lower portion of the cap, thus leaving the entire inner surface of the cap from near the lower edge thereof to the top free of any inward holding projections, threads or other means to become filled up and corroded by the bottle contents.

Thus by means of the present improvement I am able to provide a cap which can be readily made without the use of threads or other similar holding means, and in which the lower edge of the cap can be strengthened by means of a rolled or curled portion, which makes the cap sanitary and free from certain disadvantages present in a raw or free edge cap. By means of the rolled edge the cap can be removed by the use of a coin, since this rolled edge so strengthens or stiffens the lower edge of the cap that a coin may be used to engage this lower strengthened edge to pry off the cap without mutilation or destruction to the edge, although the cap is made of thin metal. The annular holding portion of the cap is so located that the impressing thereof to secure it to the bottle will not be interfered with by the reinforced lower edge or be injured by any implement used to pry off the cap. Moreover the metal above the curled edge can be impressed more readily than is possible with the rolled edge which, because of its stiffened formation, resists such inward pressure and also resists the prying off of the cap. Consequently the present cap can be more easily removed by the use of a coin as the unstiffened annular bead 11 will yield more quickly than would the stiffened lower edge were this bent under the container shoulder.

Most catchup caps heretofore devised have usually been provided with threads requiring the glass neck of the bottle to be similarly formed and there are certain disadvantages in such constructions other than those already pointed out, among which are the expense of forming the caps with threads as well as the bottle, and the time required to turn the cap on and off, all of which are material factors in the manufacture and quick handling of devices of this kind. Aside from this, the ordinary threaded catchup cap requires a separate sealing medium for the bottle usually in the form of a separate cap or cork, which the present improved cap does away with, thus enabling this cap to not only take the place of two but to be made at much less expense, to be more easily handled and more quickly applied, as well as removed, and also more efficiently used.

It will be seen from the foregoing that this improved catchup cap has the straight

side walls of its skirt terminating at its lower edge in an inwardly bent wall and an outwardly bent or flaring wall forming an annular holding bead, and that the outwardly bent wall terminates in a rolled or beaded edge not only adjacent to but practically extending into or terminating in the recess formed by said bent walls, so that the rolled or beaded edge and the holding means or bead of the cap are both located at the extreme lower edge of the cap and cooperate as hereinbefore stated, to reinforce each other without however, either interfering with the action of the other, and this double reinforcement of one above the other enables the cap to be pried off without the mutilation or destruction of the straight side walls of the cap.

Thus I have provided an improved cap comprising a top and a depending skirt having a curled or rolled lower edge thus materially simplifying and reducing the cost of manufacture thereof. The cap is merely placed on the bottle and by a suitable machine the metal above the rolled edge is inset under the shoulder of the container, whereby the cap is efficiently held on to the bottle. Subsequently the purchaser of the sealed package can by the use of a mere coin quickly pry off the cap, and when it is desired to reseal the bottle the cap can be readily snapped on. Thus, I believe I have provided the most inexpensive, easiest handled and applied catchup cap that has so far been devised, free of any objections heretofore present in catchup caps.

It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A pry-off and reusable metal cap comprising a top and a long depending skirt forming a catsup cap, said skirt having in proximity to its lower edge two inwardly projecting walls forming a holding portion formed in the cap while the cap is on the container and functioning under the shoulder of the container as the sole holding element of the cap, the lower inwardly projecting wall terminating at its lower edge in a curled or reinforced portion spaced from said holding portion whereby a coin may be inserted for prying off the cap and thereafter the cap readily snapped on, said skirt having a smooth and unbroken surface from its top to its holding portion.

2. A pry-off and reusable metal cap com-

- prising a top and a depending skirt having in proximity to its lower edge two annular inwardly projecting walls forming an annular holding bead formed in the cap
- 5 while the cap is on the container and functioning under the shoulder of the container as the sole holding element of the cap, the lower inwardly projecting wall terminating at its lower edge in a curled or reinforced
- 10 portion spaced from said holding bead whereby a coin may be inserted for prying off the cap and thereafter the cap readily snapped on, said skirt having a smooth and unbroken surface from its top to its holding bead.
- 15 3. A two-piece pry-off and reusable metal cap comprising a top and a depending skirt interlocked therewith and having a length at least substantially as great as its diameter
- 20 4. The method of sealing a catchup receptacle, which consists in applying to a catchup receptacle having a shoulder spaced remotely from the mouth formed portion thereof, a pry-off and reusable metal cap comprising a top and a depending skirt having a length at least substantially as great as its diameter and having at its lower edge a pre-formed annular curled or reinforced portion and having from its top to said curled edge a smooth and unbroken surface, and then while the cap is on the container insetting that part of the smooth skirt immediately above said curled edge to form a pair of annular inwardly projecting flaring walls forming an annular holding bead functioning under the shoulder of the container and independently of the curled edge as the sole holding element of the cap, the lower flaring wall being laterally spaced from the container neck whereby a coin may be inserted under the curled edge for prying off the cap, the cap being readily reusable by subsequently snapping it on.
- 25 Signed at 1822 Park Row Building, New York, New York, this 15th day of January 1924.
